ALTERNATING CURRENT CONTROL
SYSTEM

Foster E. Weld, Newton, Mass., assignor to The Gamewell Company, Newton, Mass., a corporation of Massachusetts

Original application February 14, 1933, Serial No. 656,664. Divided and this application March 15, 1934, Serial No. 715,596

2 Claims. (Cl. 177—354)

This invention relates to alternating current control systems and more particularly to arrangements responsive to signal impulses or current impulses generally, this application being a division of my copending application Serial No. 656,664, filed February 14, 1933.

One of the main objects of the invention is to provide in signaling systems of the type described in the above-mentioned copending application Serial No. 656,664 alternating current signal responsive devices which produce unidirectional current impulses, for the purpose of controlling with alternating current supplied signal loops receiving and repeating apparatus operative with direct current only, and to supply outer signal circuits as well as direct current operative signal responsive devices with electric energy derived from a source of alternating current.

In another aspect, the invention contemplates an electric system with a control circuit that is normally in a certain electric condition, and under such condition correspondingly affects an associated reception or controlled circuit, any change in the condition of the control circuit causing a related change in the condition of the controlled circuit. The control circuit may, for example, be normally closed, when it causes no current flow in the controlled circuit, but causing a controlled current flow when it is opened, or it may be normally open and cause the interruption of a current normally flowing in the controlled circuit.

A further object of the invention is to provide an electric system containing a circuit which is normally closed and supplied with alternating current and an associated circuit which furnishes unidirectional electromotive force whenever the alternating circuit is interrupted.

Still another object of the invention is to provide a signaling system using alternating current in a signal dispatching circuit but (receiving station equipment being usually not well suited for operation with such current) permitting the operation of the receiving apparatus with direct current, and at the same time transmitting alternating current signal impulses originating in the dispatch circuit to the receiving apparatus in the form of direct current impulses.

These and other aspects and objects will be apparent from the following detailed description illustrating the genus of the invention with reference to a concrete embodiment thereof. The description refers to a drawing, in which:

Fig. 1 is a circuit diagram of a practical embodiment of my invention; and

Fig. 2 is a simplified detail of the alternating current control arrangement of Fig. 1.

In Fig. 1, L denotes a control circuit or signal loop with a group of circuit control means, as for example signal formulating stations N herein also referred to as alarm boxes. Any suitable number of loops may be employed in order to provide the area served by the signal system with a sufficient number of alarm boxes, an additional loop L' being shown in Fig. 1. According to the practice common in fire alarm systems, the embodiment of the invention herein described has normally closed loops, signals being formed by interrupting the loop circuits by suitable coding means. However, normally open loops in which signals are formed by closing the loop circuits could be used with the present invention, as will become evident from the following explanations.

The loops L with alarm boxes N are supplied with alternating current of suitable voltage and frequency from supply busses 121, 122, through supply transformers 110, with supply primaries 157 and supply secondaries 156. Each loop has a line transformer T with control primaries 151, 152, also referred to as control and balancing inductances, respectively, having terminals 159 and 158 on either side of tap 150. An adjustable impedance 155, herein also referred to as balancing impedance, is provided which approximately reproduces the electric characteristics of loop L. Secondary 156 of supply transformer 110 is connected between tap 150 and terminal 170 of the impedance 155, loop L with control means N is connected between terminals 170 and 159, and impedance 155 between terminals 158 and 170. It is apparent (especially from Fig. 2, which groups these elements in a somewhat simplified, but equivalent manner), that the electromotive forces of primaries 151 and 152 balance each other, provided that the primary windings and loop L and impedance 155, respectively, are electrically substantially equivalent, in which case no electromotive force is induced in secondary 160 of transformer T, so long as the loop is closed.

Secondary 160 supplies the input terminals 161, 162 of rectifier bridges 163, 164 of conventional design, supplying output terminals 166, 167 and 168, 171, respectively, with unidirectional current, if an electromotive force is impressed in secondary 160. In Fig. 1, terminals 166, 167, 168 of all line transformer circuits are denoted with these like numerals, whereas the fourth terminals of the loop have numerals 171, 172, etc. All terminals 166 and 168 are joined by bus 8 and all terminals 167 are joined by bus 9, whereas ter-

minals 171, 172, etc., are connected to corresponding line contacts 1, 2, etc. of selector relay S.

The selector relay S is of the type commonly used as preselector in automatic telephone installations and may have any suitable conventional design. The selector herein indicated comprises a stepper magnet 30 with a vibrator arm 32, a vibrator contact 31 normally making connection with the arm 32 (the contacts being bridged by a circuit suitable to suppress sparking), in series with the magnet, a number of line contacts 1, 2, 3, etc., one line contact being provided for each loop, and a wiper 35 which is in well known manner mechanically or otherwise controlled by armature 32 so that it moves over the line contacts step by step so long as magnet 30 remains energized, thereby consecutively connecting the contacts with the selector lead 36. In well known manner, the wiper progresses always in the same direction and, having a sliding contact at each end, again touches the first line contact 1 with one of these two sliding contacts after the other sliding contact has left the last line contact.

The cut-off relay C has a cut-off magnet 81 controlling a stepper magnet switch 82 with stepper contact 83 and a change-over switch 84 with cut-off contact 85 and holding contact 86. Switch member 84 is connected through resistance 173 to one terminal of magnet 81, and stepper switch member 82 is connected to the other terminal of 81, and, together with that terminal, to one of the output terminals of rectifier 174, to be described more in detail hereinafter.

In a manner similar to that shown and described in the United States Letters Patent Nos. 1,467,301 and 1,602,065, granted to Clarence E. Beach September 11, 1923 and October 5, 1926, respectively, the register M' has normally open contacts 295, 296 and a paper feed train, and switch operating devices which retain contacts 295, 296 normally open and close them effectively only for a short time just before the feed train terminates its run. As shown in Fig. 1, block 311, quickly turned by spring 312 upon energization of magnet 313, closes at that time the contacts during a period which is so short as to have no influence upon the circuit, whereas, towards the end of the slow return movement of 311, it closes contacts 295, 296 for a time which is sufficient to effect the desired result which will appear hereinafter.

Stepper magnet 30 is connected between bus 9 and stepper magnet switch 82, which normally connects it with bus 8 through conductor 46, and also with one terminal of cut-off magnet 81. The other side of the magnet 81 is connected, through resistance 173, to change-over switch 84 which connects it normally to wiper 35, through alarm circuit conductor 45. The holding contact 86 is connected to the positive terminal of aforementioned local rectifier 174. The negative terminal of that rectifier is connected through conductor 46 to the bus 8 and through said conductor 46 to contact 82 and magnet 81 as above described, and the input terminals are connected to the alternating current supply busses 121 and 122. Magnet 81 can be short circuited by normally open contacts 295, 296 of the register M' whose magnet 313 is connected between conductors 45 and 46.

The reception circuit A comprises reception circuit conductors 45 and 46 connected to wiper 35 and the negative terminal of rectifier 174 respectively, and signal repeating devices such as

tape recorders, gongs, or any other suitable recording, acoustic, or optic signal manifesting means, which are indicated at 50. The circuits supplied from the controlled rectifiers 163, 164, 167, 168, etc. may be termed controlled reception circuits, whereas the circuit supplied from rectifier 174 will be referred to as holding circuit.

The arrangement shown in Fig. 1, especially suited for operation with alternating current, but in principle an adaptation of the circuit of Fig. 1 of the above-mentioned copending application Serial No. 656,664, with a cut-off relay added and employing instead of the line relays E of that circuit what may be called, for want of a better term "switchless alternating current relays", constituted by control devices according to the present invention operates as follows: Under normal conditions, when the loops L, L', etc., are closed, the electromotive forces of the line transformer primaries 151, 152, supplied from busses 121, 122, balance one another and no electromotive force is induced in 160, so that the station circuit does not carry any current. Upon interruption of a loop, say L, connection between 159 and 170 is broken, 151 carries no current, and the electromotive force of 152 induces a current in the supply circuit of rectifiers 163 and 164, so that unidirectional electromotive forces appear across terminals 166, 167, and 168, 171, respectively. The unidirectional potential across busses 8 and 9 supplies current to circuit 8-46-82-31-32-30-9 which energizes stepper magnet 30, the latter advancing wiper 35 until it touches line contact 1. At this moment, a circuit 168-8-46-81-173-84-85-45-35-1-171 is closed, energizing cut-off magnet 81 which attracts its armatures 82 and 86, opening the above traced stepper magnet circuit at 82, and changing member 84 from cut-off contact 85 to holding contact 86. This action instantly interrupts the stepping action of magnet 30, arresting the wiper at the appropriate line contact 1, and establishing a holding circuit for cut-off magnet 81 from the negative terminal of rectifier 174, through 46-81-173-84-86 to positive terminal of rectifier 174, so that no other loop can interfere with the signaling loop L during energization of 81. After loop L has finished its signal, that is, shortly before the feed train of register M' has run down, contacts 295, 296 are closed, short-circuiting magnet 81, which thereupon releases members 82 and 86, restoring the circuit to normal condition. The resistance 173 prevents short-circuiting of the rectifier 174 during such closure of contacts 295 and 296.

During the signaling period, signals are received at register M', or other apparatus, as 50, connected to the alarm circuit. Unidirectional current is furnished by the rectifier bridge 174 for the holding circuit of relay C. In this manner, a signaling circuit supplied with alternating current exclusively is provided, which combines the advantages of signal loops energized with alternating current and of a repeater circuit operated with unidirectional current, without involving the use of relays and local supply batteries.

If any one of the loops, for example loop L, remains open indefinitely, the contacts 295 and 296 of register M' will cause momentary deenergization of magnet 81 and during such deenergization of 81, contacts 82 will close the circuit through magnet 30 and cause stepping of wiper 35. If no other open loop circuit is found, wiper 35 continues to step around until it again arrives at

contact 1 where it again stops and causes a second actuation of register M'.

This action is repeated continuously so long as loop L remains open, thus calling the operator's attention to the faulty condition of the system, which can be rendered responsive to the sound loops by manually interrupting the rectifier output leads of the faulty loop.

It will now be understood that my new arrangement can be utilized for normally open control circuits. Assuming, for example, that in Fig. 2 the switch at L is normally open and that alternating current is continuously supplied at 157, the controlled circuit including secondary 160, is normally supplied with current caused by the electromotive force induced in winding 152. Upon closure of the control circuit at L an electromotive force in 151 is added to that in 152, causing the electromotive force in secondary 160 to decrease or to disappear, which effect can be appropriately utilized to obtain desired functions in the controlled circuit including winding 160.

It will now be evident that the herein-described arrangement can be used in any signaling circuit employing normally open or normally closed signal initiating circuits supplied with alternating current and that it is useful not only in signaling installations but in every case where it is desirable to have a device without switching elements, which effects a current change in a controlled circuit carrying either alternating current or direct current, upon a change in the current conditions in a controlling alternating current circuit.

It should be understood that the present disclosure is for the purpose of illustration only and that this invention includes all modifications and equivalents which fall within the scope of the appended claims.

I claim:

1. An electric signaling system of the character described comprising a source of alternating current; a plurality of signal loops each serially including signal initiating stations, a supply transformer secondary supplied from said source and a control transformer primary; balancing circuits connected to each of said supply transformer secondaries in parallel to said control primaries, each balancing circuit having a balancing pri-

mary coupled with the respective control primary; controlled secondaries coupled to each pair of said primaries; rectifying means for each of said loops supplied from respective ones of said controlled secondaries; a direct current signal reception circuit including a signal manifesting means and a selector switch for consecutive connection of said manifesting means with respective ones of said rectifying means upon energization thereof by an abnormal signal loop; means for arresting said selector switch for connection of said manifesting means with said abnormal loop; holding means for maintaining said selector switch in arrested position; and a rectifier supplied from said source for energizing said holding means.

2. An electric signaling system of the character described comprising a source of alternating current; a plurality of signal loops each serially including signal initiating stations, a supply transformer secondary supplied from said source and a control transformer primary; a direct current signal reception circuit including signal manifesting means and a selector switch having a stepping magnet for actuation thereof and a plurality of contacts arranged for consecutive connection thereof to said manifesting means; balancing circuits connected to each of said supply transformer secondaries in parallel to said control circuits, each balancing circuit having a balancing primary coupled with the respective control primary; controlled secondaries coupled to each pair of said primaries; and two rectifying means connected with their input terminals in parallel to each controlled secondary, one of said rectifying means supplying said stepping magnet and the other being associated with said reception circuit through connection to one of said contacts, the current induced in one of said controlled secondaries upon signal initiation by changing electric conditions in the corresponding loop causing said first rectifying means to energize said stepping magnet for actuation of said switch until it establishes connection of said corresponding loop to its contact in the manifesting circuit, for reception of signal impulses through said secondary, said other rectifying means and said contact.

FOSTER E. WELD.
